(57) **CLAIM**

The ornamental design for a string of lights, as shown and described.

DESCRIPTION

FIG. 1 is a front, right and top perspective view of a string of lights, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof; and, FIG. 10 is an enlarged view of portion of FIG. 2 thereof. The dashed broken lines shown in the drawings illustrate portions of the string of lights that form no part of the claimed design.

The dot-dash broken lines depict the boundaries of the enlargements that form no part of the claimed design.

The string of lights are shown with symbolic breaks in its length. The appearance of any portion of the article between the break lines forms no part of the claim. The brackets in the drawings indicate that the article includes features shown at opposite sides of the break lines and otherwise form no part of the claimed design.
